NECKTIE

Alfred F. Taborski, Buffalo, N. Y.

Application August 14, 1946, Serial No. 690,425

8-Claims. (Cl. 2—150)

1

This invention relates to neckties, and particularly to those of the preformed type.

An object of the invention is to provide an improved, preformed and attractively appearing necktie, in which the drape or breast pieces may be easily and quickly attached to and detached from the knot portion, to enable differently appearing drapes to be interchangeably attached to the knot portion; with which no tools are required to attach or detach a drape; with which accidental or unintentional detachment of a drape from the knot portion is unlikely; which will have the appearance of the four-in-hand tie; and which will be relatively simple and inexpensive.

Other objects and advantages will be apparent from the following description of several examples of the invention, and the novel features will be particularly pointed out hereinafter in connection with the appended claims.

In the accompanying drawing:

Fig. 1 is a side elevation, partly in section, of a tie constructed in accordance with this invention;

Fig. 2 is a side elevation of a part of the construction shown in Fig. 1 but with a slight modification thereof;

Fig. 3 is a sectional elevation of another tie construction in accordance with the invention but illustrating another embodiment thereof;

Fig. 4 is a side elevation similar to Fig. 1 but illustrating another embodiment thereof;

Fig. 5 is a side elevation of part of a tie embodying the invention, but showing another modification thereof; and

Fig. 6 is a rear elevation of the tie shown in Fig. 5.

In the embodiment of the invention shown in Fig. 1, the tie includes a knot portion 1 of any suitable material having a textile or other ornamental covering 2. Arms 3 (one shown) extend laterally from opposite sides of the knot portion, adjacent its upper end, and terminate in loops to which may be coupled an elastic band (not shown) that encircles the neck band to confine the tie thereto.

The knot portion is provided at its lower end with a downwardly opening recess 4. In this recess is a removable pin or element 5 that depends below the recess when the pin is with the recess to the full extent possible. A drape or breast piece 6 of textile or other suitable material is gathered at one end around and attached to the lower part of pin 5, from just within recess 4 downwardly, so that the drape will

2

appear to depend from the knot portion with no unsightly opening. The gathered drape is secured to the pin in any desired manner, such as by sewing, and nicely fills the recess opening.

5 An elastic element 7 is connected under tension between the knot portion and the pin or element 5, and resiliently urges the pin into recess 4 so as to hold the gathered end of the drape within recess 4. In the example shown, 10 the pin 5 has a transverse passage 8, and the elastic element 7 is an elastic cord threaded through passage 8 and having its ends connected to an eye 9 which is detachably engaged over a hook 10 secured on the rear face of the knot portion near the upper part thereof. The cord is stretched or under tension while eye 9 is engaged over hook 10, and resiliently holds the drape end within recess 4.

To remove the drape 6 for substitution of another, one merely disengages eye 9 from hook 10, and then the drape may be pulled from recess 4. A new drape with its pin 5 and cord 7 is then inserted into recess 4, cord 7 stretched, and eye 9 engaged over hook 10.

25 In Fig. 2 the construction is similar to that shown and described in connection with Fig. 1 except that the cord 7A is a single stretch passing through passage 8 and attached to a cross bar 11 which, when lying along the cord, enables the cord and bar to be passed through the passage 8 in either direction to engage or disengage the cord therewith, and when crosswise of the cord while the cord is in passage 8, will prevent withdrawal of the cord from that passage. The other end of the cord is looped to form the eye 9 that may be engaged over hook 10.

In Fig. 3 the construction is similar to that of Fig. 1 except that the elastic element 7 is connected at one end to a hook 16 which is engaged 40 in an aperture 17 in pin 5. The other end of element 7 is received in a groove 18 in the rear face of the knot portion, beneath cover 2, and anchored at its other end to the upper part of the rear face of the knot portion, with the element 7 under tension.

In Fig. 4 the construction is similar to that of Fig. 1 except that a clip 12 has arms 13 extending around pin 5 and tightly gripping it, and a hook 14 extending upwardly from arms 13. The 50 elastic cord or element 7 carries an eye 15 which detachably engages with hook 14 and at its other end is secured to the rear face of the knot portion near its top, with the cord under tension.

In Figs. 5 and 6 the construction is similar to 55 that shown in Fig. 1 except that the elastic ele-

ment 7 is an elastic cord passed through a passage 8 in the pin 5 and its ends secured to a hook 19 which is engaged in any one of several recesses 20 in the rear face of the knot portion, the covering 2 being separated enough to expose the recesses 20 as shown in Fig. 6.

It will be observed that in all of the embodiments, the stiffening pin 5 to which the upper end of the drape is secured is resiliently and removably held in a recess in the lower end of the knot portion, and the elastic element may be manipulated to release the stiffening pin and enable removal of the drape without the use of tools. While the drape is shown as secured in this manner to the knot portion of a four-in-hand tie, it will be understood that wings of a bow tie may be similarly, and resiliently but detachably connected to the knot portion of a bow tie.

It will be understood that various changes in the details, materials and arrangements of parts, which have been herein described and illustrated in order to explain the nature of the invention, may be made by those skilled in the art within the principle and scope of the invention, as expressed in the appended claims.

I claim:

1. In a preformed necktie, a knot portion having a recess in its lower part and opening downwardly, a pin movable endwise loosely into and out of said recess through said opening, and when within said recess having a lower end portion depending below said knot portion, a drape having an end fitted over and around said pin and secured thereto, said drape having its end portion that is attached to said pin extending into said recess, and an elastic element coupled under tension between said knot portion and said pin and resiliently urging said pin into said recess.

2. In a preformed necktie, a knot portion having a recess in its lower part and opening downwardly, a pin movable endwise loosely into and out of said recess through said opening, and when within said recess having a lower end portion depending below said knot portion, a drape having an end fitted over and around said pin and secured thereto, said drape having its end portion that is attached to said pin extending into said recess, and an elastic cord coupled at one end to said knot portion well above said opening into said recess, and at its other end to said pin below said opening, said cord when coupled being under tension, and one of its said coupled ends being detachable to enable separation of said pin and knot portion.

3. In a preformed necktie, a knot portion having a recess in its lower part and opening downwardly, a pin movable endwise loosely into and out of said recess through said opening, and when

within said recess having a lower end portion depending below said knot portion, a drape having an end fitted over and around said pin and secured thereto, said drape having its end portion that is attached to said pin extending into said recess, and an elastic element detachably coupled under tension between said knot portion and said pin and resiliently urging said pin into said recess.

4. In a preformed necktie, a knot portion having a recess in its lower end, a pin insertable endwise partially into and out of said recess, a drape secured at one end to and concealing the lower end portion of said pin, and having its said one end within said recess when said pin is within said recess and an elastic element coupled under tension between said pin and said knot portion and resiliently urging said pin into said recess.

5. A necktie substantially as set forth in claim 4 in which said elastic element is an elastic cord stretched between connections to said pin and said knot portion.

6. In a preformed necktie, a knot portion having a recess in its lower end, a pin insertable endwise partially into and out of said recess, a drape secured at one end to and concealing the lower end portion of said pin, and having its said one end within said recess when said pin is within said recess and an elastic element coupled under tension between said pin and said knot portion and resiliently urging said pin into said recess, said element being an elongated stretchable member attached at its ends to said pin and said knot portion.

7. In a preformed necktie, a knot portion having a recess in its lower end, a pin insertable endwise partially into and out of said recess, a drape secured at one end to and concealing the lower end portion of said pin, and having its said one end within said recess when said pin is within said recess, and an elastic element coupled under tension between said pin and said knot portion and resiliently urging said pin into said recess, said element being an elongated stretchable member attached at its ends to said pin and said knot portion, and one of said end attachments of said member being detachable to enable complete separation of pin and knot portion.

8. In a preformed necktie, a knot portion having an outwardly opening recess, a stiffening pin removably and loosely extending into said recess, and having an outwardly extending end, an ornamental member secured over said extending end of the pin and with the pin extending somewhat into said recess, and an elastic element connected under stress between said pin and said knot portion, to resiliently hold said pin within said recess.

ALFRED F. TABORSKI.
